SKILL RADIO AND RECORDING
MANIPULATOR

Herman L. Grundstein, Bronx, N. Y.

Application October 3, 1935, Serial No. 43,444

16 Claims. (Cl. 250—20)

This invention relates to radio receiving apparatus and has special reference to a skill operated means for closing radio circuits.

One object of the invention is to provide a novel combination of radio receiver and skill operated means for closing the circuits of such receiver.

A second important object of the invention is to provide, in connection with the tuning condenser of a radio receiving set, skill operated means controlling the setting of such set.

A third object of the invention is to provide a novel circuit closing arrangement for radio circuits, the arrangement being operated by the dropping of movable playing pieces into certain pockets.

A fourth object of the invention is to provide, in such apparatus, electrically controlled means for ejecting a playing piece from a pocket so that it may move to the next pocket.

A fifth object of the invention is to provide novel means whereby a radio receiving set may have its tuning condenser actuated to stop at any desired station receiving position.

A sixth important object of the invention is to provide novel circuit arrangements for such apparatus.

With the above and other objects in view, the invention consists in general of certain novel details of construction and combinations of parts hereinafter fully described, illustrated in the accompanying drawings and particularly pointed out in the claims.

In the accompanying drawings like characters of reference indicate like parts in the several views, and:

Figure 1 is a plan view to small scale of a skill operated device for closing circuits in a radio receiving apparatus.

Figure 2 is an enlarged plan view of the pocket portion of the device shown in Figure 1.

Figure 3 is a section on the line 3—3 of Figure 2.

Figure 4 is an enlarged detail section on the line 4—4 of Figure 3.

Figure 5 is a detail section on the line 5—5 of Figure 3.

Figure 6 is a detail section on the line 6—6 of Figure 3.

Figure 7 is a diagram showing the wiring of the invention.

In illustrating the invention it has been shown in connection with a game of skill of the type of a bagatelle board, this being a board inclined upwardly from the front or players station. It is,

however, to be understood that the invention is not limited to this particular game of skill and that the game here shown and described as an example is to be taken as typical of any game of skill having a series of pockets into which playing members such as balls, blocks, disks or the like are driven by the skill of the player.

Accordingly, whenever game board is mentioned hereafter it is to be understood in the broad typical sense above stated. Also, for convenience, the playing members will be herein-after referred to as "balls" and this term is to be understood as not only including balls but including in addition any form of playing member adapted to be received in a pocket.

In the particular form of game board here shown there is provided a table 10 having a depressed well 11 at its forward end. Just forward of this well there is a row of pockets 12 separated from the well by a wall 13. Around this table 20 extends a cushion wall 14 which is semicircular at its forward end. Partitions 15 extend rearwardly on the table from the spaces between the pockets and terminate forwardly behind of the line of pockets and rearwardly on a transverse 25 line spaced forwardly from the center of the semi-circular portion of the wall. Other similar partitions 16 divide the pocket space from the side walls of the table and provide a playing chute 17 and a return chute 18. The main part of the 30 table 10 inclines upwardly from front to rear and the part containing the pockets 12 inclines downwardly from right to left as in Figure 3. A plunger 19 serves to actuate a ball 20 and the device is provided with any suitable form of coin 35 control as indicated at 21. It is to be observed that there are eight runways formed by the partitions 15 and 16 but there are only seven pockets 12, the runway between pockets 5 and 6 (as indicated in Figures 1, 2, and 7) being closed as 40 at 22.

With such a device as this a ball 20 is placed in position to be struck by the plunger or cue 19. When so struck with the proper degree of force the ball will move up the chute 17, move to the left after leaving the chute 17 and roll back into the desired runway. If, on the contrary, the proper degree of force is not used the ball will either pass into some other runway than that desired or will return to the well 11 down the 45 chute 18. A ball entering a runway will roll forward and drop in the pocket at the forward end of that runway unless the pocket has been filled. This is an ordinary arrangement for such boards.

There will now be considered the specific features of such a board which enter into this invention.

Referring to Figure 7, there is provided a battery 23 from which extends the wires 24 and 25. In pocket 12 No. 1 there is a circuit closer 26 which is normally open but is closed by the dropping of a ball into said pocket. As here shown, each of the pockets 12 is of a diameter 10 to closely fit the balls used and is of a depth of about one-half its diameter. The circuit closer 26 includes an arcuate spring member 27 one end of which fits in an annular rabbet 28 at the upper end of the pocket. The other end of the 15 spring 27 normally projects into the pocket space proper but, upon the seating of a ball in this pocket, is pushed outwardly into the rabbet and engages a fixed contact 29 sunk in the wall of the rabbet. Each of these contacts is provided 20 with an ear 30 flush with the table 10 and which has a countersunk screw 31 (see Figure 4) extending down into a recess 32. On the lower end of this screw is a nut 32 for securing a lead wire 33, the table being channeled as at 34 to accommodate this lead wire. Similarly arranged circuit closers will be found in pockets 12 Nos. 3, 4, 25 6, and 7 but these will not be specifically described or have reference characters applied to their several parts, the foregoing being deemed sufficient for an understanding of all like circuit closers. In each of pockets 12 Nos. 2 and 5 there is provided a bottom 35 actuated by a solenoid 36 to rise and eject a ball held therein, the bottom being normally lowered to enable a ball to 30 seat in such pocket. The circuit breaker is connected by wire 33 with one terminal of the solenoid of pocket No. 2 and by a branch 37 to one terminal of the solenoid of pocket No. 5, the two solenoids being thus connected in multiple to one side of the circuit breaker. A wire 38 connects the other side of the solenoid to the wire 24. The remaining terminals of the solenoids 36 are connected by wires 39 to the wire 25. Also, branch wires 40 connect a bell 41 across the wires 37 45 and 25.

Power leads or wires 42 and 43 are provided and in each of pockets Nos. 3, 4, 6, and 7 there is provided a normally open circuit closer 44 one side of which is connected to the wire 43 by a wire 45 while the other side of the circuit closer is connected by a wire 46 through a lamp 47 to the wire 42. Thus, whenever a ball drops in one of these pockets a lamp circuit is closed and the corresponding lamp lights. A wire 48 leads from the wire 42 to the speaker 49 and a power input terminal of a radio receiving set indicated in general at 50 but not having its internal circuits shown since these do not enter into the present invention.

The other power terminal of the set is connected by branch wires 51 to one side of each of two circuit closers 52 respectively mounted in the pockets 12 Nos. 3 and 6. The other sides of these circuit closers are connected by wires 53 with the wire 43. Thus if a ball drops in either pocket 3 or pocket 6 the power circuit of the set is closed. The set also has feed wires 54 for the filament circuit.

The movable plates of the tuning condenser of the set 50 are shown at 55 as outside the set for convenience in illustrating the device but they are actually in the casing of the set. These plates are mounted on a shaft 56 and are urged 75 to rotate in a clock-wise direction by a spring

57. Normally the plates are held in the inactive position shown by a lever 56' fixed on the shaft 56 and a latch 58 which forms the armature of a magnet 59 and is moved to release the plates upon energization of the magnet. Similarly, 5 latches 60 and 61 controlled by the magnets 62 and 63 are located to catch and retain the lever 56' at different points in the path of the movement of the plates, a stop 64 being provided to limit their movement. Wires 65 connect the wire 10 25 to one terminal of each of the magnets. In pocket 12, No. 4 is a normally open circuit closer 66 having one side connected by a wire 67 to the magnet 59 and its other side connected by a wire 68 to the wire 24. Thus when a ball drops 15 in pocket No. 4 a circuit through the magnet 59 is established and the plates released to turn and be engaged by the latch 60. Between the pockets Nos. 5 and 6 there is a normally open circuit closer actuated to close by the passage of a ball 20 from pocket No. 5 to pocket No. 6. This circuit closer consists of a pair of fixed contacts 69 and a movable contact 70. One of the contacts 69 is connected by a wire 71 with the wire 67 and thus to magnet 59. The other contact 69 is connected by a wire 72 with the magnet 62. The contact 70 is connected by a wire 73 with the wire 24. Thus when the contact 70 closes on the contacts 69 both magnets 59 and 62 are energized and the plates 55 move to engagement by the 25 latch 61. In the pocket No. 7 is a normally open circuit closer 74 having one side connected by a wire 75 with the magnet 63 and its other side connected by a wire 76 with the wire 24. Thus, 30 when a ball drops in pocket No. 7 the third latch, 61, is released and the plates drop to engage stop 64 if they have been engaged by latch 61.

Beneath the pockets is a slide 77 supported on guides 78 and provided with openings 79 normally out of registry with the pockets and thus acting to retain balls therein. This slide is movable, in the usual manner, by the coin control to bring the openings 79 into registry with the pockets Nos. 1, 3, 4, 6, and 7 to discharge the balls held therein. At the same time provision is made to close the 40 solenoid circuits so that any balls in pockets Nos. 2 and 5 will be ejected and discharged through pockets 3 and 6. To this end, the table supports a bracket 80 carrying a pair of contacts 81 and the slide carries a bridging contact 82 which, 50 when the slide moves to open the pockets, contacts with the contacts 81. One contact 81 is connected by a wire 83 with the wire 33 and the other contact 81 is connected by a wire 84 with the wire 24 so that moving the slide to open the 55 pockets energizes the solenoids 36.

The contact 70 is in the form of a spring which (Figures 2 and 5) supports a trap door 85 arranged between guides 86 in an opening 87 in the table. The contacts 69 are fixed to a wall of this recess so that the weight of a ball rolling from pocket No. 5 to pocket No. 6 will depress the trap door and bring contact 70 into bridging contact with contacts 69.

In order to provide means to determine whether the table has been tilted a spring contact arm 88 is fixed at one end to a bracket 89 carried by the table. This arm carries a shallow cup 90 and is normally held down by the weight of a ball 91 to engage a contact 92. The contact 88 is connected to the wire 43 and the contact 92 is connected by a wire 93 through a lamp 94 with the wire 42 so that the lamp 94 is normally lit. Above the spring 88 is a second contact 95 connected by a 75

wire 96 through a lamp 97 to the wire 42. Thus, when the table is tilted the ball falls off the cup and circuit is established through the lamp 97, which may be red, and indicates that the table 5 has been tilted.

An arm 98 forms means for resetting the plates 55.

To operate the device it is necessary that there be a ball in at least one of the pockets Nos. 3 10 and 6 and that the latch 58 be released by a ball in pocket No. 4 or a ball rolling across the trap door 85.

Various methods may be used to accomplish this result. For instance, a ball may be shot to drop in pocket No. 2 or pocket No. 5. If this is 15 done a ball must be shot to drop in pocket No. 1 and thus close the solenoid circuit to eject the ball or balls from pockets Nos. 2 and 5. If there is a ball in pocket No. 2 it will move to pocket 20 No. 3 and establish the power circuit. If it is desired that the plates 55 assume position of engagement by latch 60 a ball must now be shot to fall in pocket No. 4. If, however, it is desired 25 that the plates assume their second active position a ball must be shot to pocket No. 5 which, being closed by the ball in pocket No. 1 will cause the ball to roll over the trap door and thus move both latches 58 and 60 to release position so that 30 the plates will be stopped by latch 61. A ball shot in pocket No. 7 will release this latch 61 and permit the plates 55 to assume their third active position. Obviously, the three active positions of the plates are arranged to accomplish correct 35 tuning for three different transmitting stations. Many other combinations and sequences in the closing of the circuits may be obtained but the foregoing will afford a guide as to the manner of using the invention.

There has thus been provided a novel and efficient device of the kind described and for the purpose specified.

It is obvious that many changes may be made in the form and construction of the invention without departing from the material principles 45 involved. It is not, therefore, desired to confine the invention to the exact form herein shown and described but it is desired to include all forms which come within the scope of the appended 50 claims.

50 What is claimed, is:

1. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said 55 means, circuits for said means, a power circuit, said circuits including ball actuated normally open circuit closers, a game board, and balls for said board movable thereover to effect selective closing of said circuit closers.

60 2. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said 65 means, circuits for said means, a power circuit, said circuits including ball actuated normally open circuit closers, a game board, said board having a series of ball receiving pockets therein, the circuit closers for the power circuit being located in 70 certain of the pockets and certain of the circuit closers for the latch releasing circuits being located in certain other pockets, balls adapted to be driven over said game board to fall in said pockets, and signal lights having circuits each having a 75

ing a series of ball receiving pockets therein, the circuit closers for the power circuit being located in certain of the pockets and certain of the circuit closers for the latch releasing circuits being located in certain other pockets, and balls adapted 5 to be driven over said game board to fall in said pockets.

3. The combination with a radio receiving set having a power circuit and tuning condenser plates movable over a predetermined path from 10 an initial position through a series of station receiving positions; of means urging said plates along said path, latches stopping said plates in their initial and station receiving positions, electro-magnetic means for selectively releasing said 15 means, circuits for said means, a power circuit, said circuits including ball actuated normally open circuit closers, a game board, balls for said board movable thereover to effect selective closing of said circuit closers, and signal lights arranged to indicate the 20 closing of said circuits.

4. The combination with a radio receiving set having a power circuit and tuning condenser plates movable over a predetermined path from an initial position through a series of station receiving 25 positions; of means urging said plates along said path, latches stopping said plates in their initial and station receiving positions, electro-magnetic means for selectively releasing said 30 means, circuits for said means, a power circuit, said circuits including ball actuated normally open circuit closers, a game board, said board having a series of ball receiving pockets therein, the circuit closers for the power circuit being located in certain of the pockets and certain of the 35 circuit closers for the latch releasing circuits being located in certain other pockets, balls adapted to be driven over said game board to fall in said pockets, and signal lights arranged to indicate the closing of said circuits.

40 5. In combination with radio receiving set having a power circuit and tuning condenser plates movable over a predetermined path from an initial position through a series of station receiving positions; of means urging said plates along said 45 path, latches stopping said plates in their initial and station receiving positions, electro-magnetic means for selectively releasing said means, circuits for said means, a power circuit, said circuits including ball actuated normally open circuit 50 closers, a game board, balls for said board movable thereover to effect selective closing of said circuit closers, and signal lights having circuits each having a ball actuated normally open circuit closer positioned adjacent a respective first mentioned 55 circuit closer to be closed simultaneously therewith.

6. The combination with a radio receiving set having a power circuit and tuning condenser plates movable over a predetermined path from 60 an initial position through a series of station receiving positions; of means urging said plates along said path, latches stopping said plates in their initial and station receiving positions, electro-magnetic means for selectively releasing said 65 means, circuits for said means, a power circuit, said circuits including ball actuated normally open circuit closers, a game board, said board having a series of ball receiving pockets therein, the circuit closers for the power circuit being located in 70 certain of the pockets and certain of the circuit closers for the latch releasing circuits being located in certain other pockets, balls adapted to be driven over said game board to fall in said pockets, and signal lights having circuits each having a 75

ball actuated normally open circuit closer positioned adjacent a respective first mentioned circuit closer to be closed simultaneously therewith.

7. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, said board having other ball receiving pockets, ball ejectors in said last pockets, electro-magnetic means connected to said ball ejectors to operate the same, and a circuit for said circuit closers including a ball actuated normally open circuit closer, said board being arranged to direct the ejected balls to certain of the first mentioned pockets.

8. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, said board having other ball receiving pockets, ball ejectors in said last pockets, electro-magnetic means connected to said ball ejectors to operate the same and a circuit for said circuit closers including a ball actuated normally open circuit closer, said board being arranged to direct the ejected balls to certain of the first mentioned pockets, said game board having a further pocket holding the last mentioned circuit closer.

9. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, signal lights arranged to indicate the closing of said circuits, said board having other ball receiving pockets, ball ejectors in said last pockets, electro-magnetic means con-

nected to said ball ejectors to operate the same, and a circuit for said circuit closers including a ball actuated normally open circuit closer, said board being arranged to direct the ejected balls to certain of the first mentioned pockets.

10. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, signal lights arranged to indicate the closing of said circuits, said board having other ball receiving pockets, ball ejectors in said last pockets, electro-magnetic means connected to said ball ejectors to operate the same, and a circuit for said circuit closers including a ball actuated normally open circuit closer, said board being arranged to direct the ejected balls to certain of the first mentioned pockets, said game board having a further pocket holding the last mentioned circuit closer.

11. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, signal lights having circuits each having a ball actuated normally open circuit closer positioned adjacent a respective first mentioned circuit closer to be closed simultaneously therewith, said board having other ball receiving pockets, ball ejectors in said last pockets, electro-magnetic means connected to said ball ejectors to operate the same, and a circuit for said circuit closers including a ball actuated normally open circuit closer, said board being arranged to direct the ejected balls to certain of the first mentioned pockets.

12. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being

located in certain of the pockets and certain of the circuit closers for the latch releasing circuits being located in certain other pockets, balls adapted to be driven over said game board to fall in said pockets, signal lights having circuits each having a ball actuated normally open circuit closer positioned adjacent a respective first mentioned circuit closer to be closed simultaneously therewith, said board having other ball receiving pockets, ball ejectors in said last pockets, electro-magnetic means connected to said ball ejectors to operate the same, and a circuit for said circuit closers including a ball actuated normally open circuit closer, said board being arranged to direct the ejected balls to certain of the first mentioned pockets, said game board having a further pocket holding the last mentioned circuit closer.

13. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, said board having other ball receiving pockets, ball ejectors in said last pockets, electro-magnetic means connected to said ball ejectors to operate the same, a circuit for said circuit closers including a ball actuated normally open circuit closer, said board being arranged to direct the ejected balls to certain of the first mentioned pockets, a slide normally closing said pockets and movable to open certain of the pockets, and means actuated by the pocket opening movement of the slide and actuating said ball ejecting means.

14. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, said board having other ball receiving pockets, ball ejectors in said last pockets, electro-magnetic means connected to said ball ejectors to operate the same, a circuit for said circuit closers including a ball actuated normally open circuit closer, said board being arranged to direct the ejected balls to certain of the first mentioned pockets, said game board having a further pocket holding the last mentioned circuit closer, a slide normally closing said pockets and movable to open certain of the pockets, and means actuated by the pocket opening movement of the slide and actuating said ball ejecting means.

arranged to direct the ejected balls to certain of the first mentioned pockets, said game board having a further pocket holding the last mentioned circuit closer, and a double circuit closer interposed in the path of an ejected ball and connected to a plurality of the latch controlling means.

15. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, said board having other ball receiving pockets, ball ejectors in said last pockets, electro-magnetic means connected to said ball ejectors to operate the same, a circuit for said circuit closers including a ball actuated normally open circuit closer, said board being arranged to direct the ejected balls to certain of the first mentioned pockets, a slide normally closing said pockets and movable to open certain of the pockets, and means actuated by the pocket opening movement of the slide and actuating said ball ejecting means.

16. The combination with a radio receiving set having a power circuit and tuning condenser plates movable over a predetermined path from an initial position through a series of station receiving positions; of means urging said plates along said path, latches stopping said plates in their initial and station receiving positions, electro-magnetic means for selectively releasing said means, circuits for said means, a power circuit, said circuits including ball actuated normally open circuit closers, a game board, said board having a series of ball receiving pockets therein, the circuit closers for the power circuit being located in certain of the pockets and certain of the circuit closers for the latch releasing circuits being located in certain other pockets, balls adapted to be driven over said game board to fall in said pockets, said board having other ball receiving pockets, ball ejectors in said last pockets, electro-magnetic means connected to said ball ejectors to operate the same, a circuit for said circuit closers including a ball actuated normally open circuit closer, said board being arranged to direct the ejected balls to certain of the first mentioned pockets, said game board having a further pocket holding the last mentioned circuit closer, a slide normally closing said pockets and movable to open certain of the pockets, and means actuated by the pocket opening movement of the slide and actuating said ball ejecting means.

HERMAN L. GRUNDSTEIN.
